UNITED STATES PATENT OFFICE.

ANDREW J. VICTORY, OF BROAD BROOK, CONNECTICUT.

PROJECTILE.

1,151,070.

Specification of Letters Patent. Patented Aug. 24, 1915.

Application filed March 9, 1915. Serial No. 13,114.

To all whom it may concern:

Be it known that I, ANDREW J. VICTORY, a citizen of the United States, residing at Broad Brook, in the county of Hartford and State of Connecticut, have invented certain new and useful Improvements in Projectiles, of which the following is a specification.

This invention relates to projectiles.

10 While a projectile involving my invention can be employed with advantage in a variety of different connections, it is of especial utility for breaking down, tearing away or destroying barriers and entanglements such 15 as are used in modern warfare to halt or check the progress of the enemy.

A device comprising the invention is simple in construction and can be inexpensively and easily manufactured.

20 In the drawings accompanying and forming part of the present specification I illustrate in detail several of the many forms of the embodiment of the invention, which to enable those skilled in the art to practice 25 the same will be set forth in detail in the following description. I do not restrict myself to this particular disclosure; I may depart therefrom in several respects within the scope of the invention defined by the 30 claim following said description.

Referring to said drawings: Figures 1, 2 and 3 are longitudinal central sectional views of slightly different forms of the projectile. Fig. 4 is a detail view of a projectable member.

Like characters refer to like parts throughout the several views.

The projectile embodies in its construction a suitable case and a projectable member in 40 the case. This projectable member may vary in its character; one that meets my conditions will be hereinafter described. The case or shell is preferably entirely closed, and it houses this projectable element, and in addition a bursting charge of a suitable explosive. The discharge of the bursting charge which may be subdivided into a plurality of sub-charges is preferably controlled by a time fuse, so that the bursting 45 charge can fulfill its function at a predetermined point or time, say for illustration a short distance in front of an entanglement or barrier. On the explosion of the bursting charge, the case or shell is bursted and 50 the projectable member released, this projectable member when released being adapt-

ed to follow approximately the trajectory of the projectile. As noted the projectable member or element is free of the shell, so that when the shell or case bursts, there is 55 nothing to impede the movement of the projectable member which follows its prescribed course to secure the desired purpose, which is as observed, the breaking down or rupturing or otherwise affecting a barrier, entanglement or some other obstruction. When I speak of the projectable member as being free of the case, I mean to imply that the two are disconnected which is of considerable importance as will be inferred. This projectable member may differ in construction 70 depending upon the particular use to which the projectile that carries it is to be put. Preferably it consists of two weights and a flexible connector therefor, a chain answering satisfactorily as such a connector and the weights being connected in some convenient manner to the terminals of the chain. This projectable element is inclosed in collapsed relation in the shell or case, and when the 75 latter bursts to free the projectable member, the weights automatically separate to elongate or open out the connector, and this relation will be maintained so that the connector with the weighted ends can break 80 down obstructions in its path.

With the foregoing general observations I will now describe more in detail what is represented by the several views and will first call attention to Fig. 1. The case or shell of this view is denoted by 2 and in general form or configuration is quite similar to the so-called shrapnel shell. The rear open end of the shell or case is closed by the plug 3 in front of which is the bursting 95 charge 4 adapted to be exploded by the time fuse 5. In front of the bursting charge and back of the head of the shell 2 is a chamber in which is freely mounted a projectable member such as that denoted in a 100 general way by 6 and shown in detail in Fig. 4. I might state at this point that the same type of projectable member is used in connection with the shells of Figs. 2, 3 and 4. In fact the only difference between the several projectiles is in the bursting charge. This projectable member 6 comprises weights as 7 and 8 of duplicate construction and the connector 9 therefor. The connector shown is in the form of a chain, its terminal links being swiveled in the eyes 10 at 105 the inner ends of the two weights 7 and 8.

These weights are unbalanced, that is to say, their centers of gravity are outside of the geometrical centers thereof, and this condition I can secure by making said weights of substantially conical or frusto-conical shape, the consequence being that I insure the spreading or separation of the weights when they are released from the shell by the bursting thereof. As a result of this the connector or chain is opened out and covers a wider field than it would otherwise do, besides which acting much more effectually than when in a tautened or practically tautened condition. The weights 7 and 8 are shown as superimposed in Fig. 1 the connecting chain 9 being wrapped partly about the same and being located in part in the space back of the weights. In Fig. 2 the case or shell 11 is exactly like that already described, as is the connector 9 in said shell or case 11. In Fig. 2 the bursting charge 12, however, is situated between the weights 7 and 8. In the shell or case 13 of

Fig. 3 the bursting charge is divided into two portions 14 and 15, the connector being located in the space between said bursting portions 14 and 15.

What I claim is:

A projectile comprising a shell, a bursting charge in the rear of said shell, and a projectable member in the shell, the projectable member being free of the shell and releasable by the shell when the latter bursts, and having weights and a flexible chain connecting the weights, the weights being located in the front end of the shell and being spaced from said bursting charge, a part of the chain being receivable in the space between the bursting charge and the weights.

In testimony whereof I affix my signature in presence of two witnesses.

ANDREW J. VICTORY.
